WITNESS:

UNITED STATES PATENT OFFICE.

ARCHIE C. ROSS, OF ATCHISON, KANSAS.

AWNING-FASTENER.

1,349,532.

Specification of Letters Patent. Patented Aug. 10, 1920.

Application filed April 6, 1920. Serial No. 371,570.

To all whom it may concern:

Be it known that I, ARCHIE C. Ross, a citizen of the United States, residing at Atchison, in the county of Atchison and State of Kansas, have invented new and useful Improvements in Awning-Fasteners, of which the following is a specification.

This invention relates to awnings, particularly to securing means therefor, and 10 has for its object the provision of a novel bracket structure whereby the top rod of an awning may be held properly in place, the bracket structure being further equipped with a guide roller or pulley about which 15 the operating cord or cords of the awnings for raising and lowering the same, may be trained.

An important object is the provision of 20 a device of this character in which means is provided whereby the top rod may be quickly and easily disengaged from the brackets when desired.

An additional object is the provision of 25 a device of this character which will be simple and inexpensive in manufacture, highly efficient in use, durable in service, and a general improvement in the art.

With the above and other objects and 30 advantages in view, the invention consists in the details of construction to be herein-after more fully described and claimed, and illustrated in the accompanying drawings in which

Figure 1 is a front elevation of my device.

Fig. 2 is a longitudinal sectional view therethrough, the awning being shown in position, and

Fig. 3 is a top plan view.

Referring more particularly to the drawings, I have shown my device as comprising 40 an attaching plate 10 of suitable size and shape provided with holes 11 for the passage of securing members such as screws or the like. Extending from the face of the plate 10 are spaced parallel outwardly extending plates 12 which are connected intermediate their ends by a transverse rivet 18. Journaled between the lower ends of 45 the plates 12 is a grooved pulley or roller 14 rotatable upon the rivet 15. At their upper ends the plates 12 are formed with recesses 16 within which is engaged the top rod A of the awning. After the rod A is

in position in the recesses it is necessary to 55 prevent it from dislodgment therefrom and to accomplish this I make use of a bolt 17 which has one end coiled about the rivet 18, as shown, and which has its other end threaded, as shown at 19. Associated with 60 this bolt is a plate 20 which is adapted to bridge the upper ends of the plates 12 and which is formed with a hole 21 for the passage of the bolt 17. I further provide a nut 22 threaded upon the bolt 17 and 65 engaging against the top of the plate 20 for holding the plate firmly in engagement with the awning rod A and with the upper ends of the plates 12.

In the use of the device it will be seen 70 that any necessary number may be employed, depending upon the width of the awning or the number of points at which it should be supported. The brackets being in position with the bolts 17 so positioned that the plates 21 will be in non-obstructing relation to the recesses 16, the top rod A of the awning is engaged in the recesses 16. The bolts 17 are then swung to bring the plates 20 over the upper ends 80 of the plates 12 to form closures for the recesses 16 and the nuts 22 are then screwed downwardly, tight against the plates 20. When necessary to remove the awning the reverse operation is followed. It will be 85 observed that the grooved pulley 14 at the lower part of the bracket provides means for guiding the operating cords used in raising and lowering the awning. The engagement of the ropes with the pulley is not 90 shown as it is believed to be unnecessary.

While I have shown and described the preferred embodiment of my invention, it is of course to be understood that I reserve the right to make such changes in the form, 95 construction, and arrangement of parts as will not depart from the spirit of the invention or the scope of the subjoined claim.

Having thus described my invention, I claim:

An awning fastener comprising a bracket including an attaching plate, a pair of spaced parallel plates extending from the face thereof and provided in their upper ends with alining recesses for the reception 105 of the top rod of an awning, a rivet extending transversely through said plates adjacent their lower ends, a grooved pulley jour-

naled on said rivet, a second rivet extending transversely through said spaced plate at their intermediate portions, a bolt having one end pivotally mounted on said second named rivet and having its other end threaded, a plate disposed upon said bolt and adapted to bridge the upper ends of

said spaced plates to form a closure for the recesses therein, and a clamping nut threaded upon the upper end of said bolt and engageable with said last named plate. 10

In testimony whereof I affix my signature.

ARCHIE C. ROSS.
